LOOSE LEAF FILING DEVICE

Filed Nov. 9, 1943

FIG. 4

13 Hans R. Feder

By Wray N. Hoffman

UNITED STATES PATENT OFFICE

2,372,717

LOOSE-LEAF FILING DEVICE

Hans Robert Federn, Oxford, England

Application November 9, 1943, Serial No. 509,609
In Great Britain November 20, 1942

11 Claims. (Cl. 129—8)

This invention relates to improvements in loose leaf filing devices of the kind in which the papers are engaged by pin or leg members through holes adjacent one edge of the papers and is readily applicable for use in conjunction with transfer arches to facilitate inspection of the papers included in the file and the insertion and removal of such papers. More particularly the invention is concerned with an improved device in which the paper engaging means is made partly or wholly of flexible material such as cord, rubber or closely coiled wire.

One of the objects of the invention is to bind securely the papers to be stored in the file by means of one or more pairs of the paper-engaging members, at least one member of each such pair having a flexible projecting end whereby the free extremities of the pair of members can be joined. It will be appreciated that although the actual length of the flexible loop or of each said loop which is formed in this way, will be of constant length, yet the effective length of the loop may need to be capable of variation in order to hold securely or bind in place the papers to be accommodated in the file. The invention enables this to be done by providing means to engage the loop in such a way as to remove the slack therein.

Another object of the invention is to enable the slack in the said loop to be taken up to a greater or lesser extent according to the variable thickness of the papers. It is also preferable for the paper-engaging members to be made flexible throughout and of substantially equal length. The term "constant length" as applied to the loop is not exclusive of such elongation as may be permitted by the elasticity of the material of which the paper-engaging members are composed and which may in fact be utilized to assist in the engagement and disengagement of the loop.

The aforesaid variation in the effective length of the loop or loops may be effected by means of one or more hooks or the like provided adjacent the paper-engaging members and preferably on the base whereon those members are mounted. When the file is to be closed the said paper-engaging members are joined together at their upper free extremities and the resulting loop (by which the papers are contained by having two holes punched therein in the usual manner each member passing through one of these holes) is then taken over the adjacent top rear edge of the block of papers and engaged with one or more of these hooks ac-

cording to the number of papers. If there are few papers to be accommodated, a greater number of hooks will have to be engaged than when there are more papers, in order to tie in the contents securely. The hooks may be mounted on the base outside the block of papers and directed away therefrom while the flexible members may be joined in known manner as for instance in the case of closely coiled wire members by having a pin fixed in the end of the one to engage frictionally in the end of the other.

A still further object of the invention is to enable such a device to be readily fitted with transfer arch means in the following way. The base may provide mountings for further paper-engaging members which can be entirely similar to those already described, and may be suitably spaced from the block of papers one in association with each of the main paper-engaging members. The ends of the latter when disconnected from one another, can be individually coupled each to its associated transfer arch member. An extension of the base can be used to carry these transfer arch members and this extension may be made collapsible to permit of horizontal contraction thereof or may be removable providing it does not also support the loop-engaging hooks.

The invention will now be described with reference to the accompanying drawing wherein:

Figure 1 shows by way of example a practical form of letter file according to the invention, provided with transfer arch means extended substantially ready for use;

Figure 2 shows the transfer arch means collapsed and the flexible paper-engaging members joined to form a loop;

Figure 3 is a similar view with the loop in position to bind the papers; while

Figure 4 shows a modified construction.

A sufficient portion of the file cover or folder for the purpose of illustrating the invention is shown in Figure 1 only. This cover consists of two sides 10 and 11 connected by a flexible back

12 to permit greater or lesser separation of the sides according to the thickness of papers in the file. Any other suitable form of adjustable back may however be substituted. The main supporting bar 13 of the device is secured in the usual way as by rivets to the inner face of one of the sides near the rear edge thereof. On this bar are located two upstanding flexible paper-engaging leg or pin members a and b, although more than a single pair can be used if desired. The position of a block of papers p to be accommodated

55

in the file is indicated in the drawing by chain dotted lines, the holes p_1 and p_2 by which the papers are engaged by the flexible members being similarly shown. Parallel with bar 13 and substantially coplanar therewith is an auxiliary bar 14 provided with laterally projecting arms 15 which slidably engage the main bar 13 so that bar 14 may be collapsed against the latter or alternatively drawn away therefrom to a distance limited by stops 16. Alternatively the bars may be connected by articulated arms 15a (as shown in Figure 4) to achieve the same result, it being preferable for the movement of the bars to take place or to be capable of taking place without appreciable relative longitudinal, as distinct from transverse displacement such as, in the collapsed condition, would result in the auxiliary bar 14 no longer lying directly opposite that part of the main bar which carries the flexible members a and b . The reason for this is that the hook or series of hooks 17 whereby the surplus of the binding loop ab is adjustably engaged can most conveniently be mounted, as shown, on the auxiliary bar 14 which, if collapsed against the main bar 13 in this substantially transverse fashion to the position shown in Figure 2, will ensure the hooks being located correctly in relation to the loop.

In addition to the hooks 17, bar 14 also carries two auxiliary flexible pin or leg members c and d which when the bars are separated as shown in Figure 1 are designed to be connected to flexible members a and b respectively to form transfer arches. When filing is completed and these transfer arches are opened, members a and b are interconnected as shown in Figure 2 and bar 14 is pushed in. It follows that if the engagement between these various flexible members is of the pin and socket type, members a and d must be provided with the one kind of connecting end-piece and members b and c with the other kind. Members a and b having been joined, the loop is drawn down over the top back edge p_3 of the papers and engaged with the necessary number of the hooks 17 to take up the slack therein as shown in Figure 3. It should be noted that if only one hook is provided, there are only two possible variations in the quantity of papers which can be securely bound, viz. enough to ensure no slack in the loop when members a and b are simply joined together (which is not really a practical possibility unless the material of which the members are composed is capable of considerable elastic extension), or enough to permit the slack of the loop being taken up by engagement on the single hook. In effect therefore the provision of one hook only, may mean absence of adjustment and in general, the greater the number of the hooks the more variation is possible in the quantity of papers which can be tightly bound in place. When disconnected, the flexible members c and d can either be joined together as shown in Figure 2 or they may be spread outwardly to be engaged under the hooks 18 which can optionally be provided near the ends of the main bar 13 as shown in Figures 3 and 4 or they may be bent inwardly and engaged under one or more of the hooks 17.

In some cases, it may not be necessary to make provision for an extensible mounting such as bar 14 for the auxiliary transfer arch flexible members c and d , it being sufficient, especially if the material of which they and members a and b are made, is very flexible, to have the said mem-

bers c and d mounted for instance on a fixed lateral extension of the main bar 13 which extension may occupy permanently, just the same position as does the bar 14 when in its collapsed position shown in Figures 2 and 3. The same will apply when there are no transfer arch facilities, in which case the members c and d will be omitted and the extension may simply serve as a supporting platform for the line of hooks 17. These hooks may be arranged in a curve or disposed in any other suitable non-rectilinear fashion to provide the desired variation in the extent to which the slack in the flexible loop can be taken up thereby. Also and particularly in absence of transfer arch means the members a and b may be of unequal length, one only being provided with the flexible projecting end which is needed to join the free extremities of the members and to form the loop.

20 I claim:

1. A filing device comprising in combination at least one main pair of paper-engaging members each with a flexible projecting end, auxiliary paper-engaging members one in association with each of the members of the main pair, separable connecting means between the extremities of each main member and its associated auxiliary member, such connecting means when disconnected being such as to permit alternative connection of the extremities of the main pair of members whereby a flexible loop of constant length can be formed and means for engaging the said loop when required for the purpose of removing slack therein and to bind the papers in the file.

2. A filing device according to claim 1 wherein the auxiliary paper-engaging members are mounted on a filing base having a lateral extension on which the auxiliary members are mounted.

3. A filing device according to claim 1 including a filing base, and wherein the loop engaging means comprises at least one hook member on said base in position to be engaged by the loop when passed over the top rear edge of the block of papers in the file.

4. A filing device according to claim 1 including a filing base on which the main paper-engaging members are mounted and a horizontally contractile extension of said base on which the auxiliary members are mounted.

5. A filing device comprising a filing base, a pair of flexible paper-engaging members on said filing base, separable connecting means between the extremities of the said members to form a loop of constant length and a plurality of hook members also on said filing base in position to be engaged one or more at a time by the said loop when passed over the top rear edge of the block of papers in the file.

6. A filing device comprising in combination at least one pair of paper engaging members, a flexible projecting end on at least one of said pair of members, separable connecting means between the extremities of said pair of members whereby a flexible loop of constant length can be formed, and means for engaging the said loop when passed back over and down behind the top rear edge of the papers held in assembled relation by said paper engaging members for the purpose of removing slack therein and to bind the papers in the file.

7. A filing device according to claim 6, wherein the loop engaging means permits of the slack in the loop being taken up to a greater or lesser extent according to the variable thickness of the

papers to be accommodated while keeping the loop substantially taut.

8. A filing device comprising in combination a filing base, at least one pair of paper engaging members thereon, a flexible projecting end on at least one of said pair of members, separable connecting means between the extremities of said pair of members whereby a flexible loop of constant length can be formed, and hook means on said filing base in position to be engaged by the loop when passed over the top rear edge of the block of papers in the file for the purpose of removing slack therein and to bind the papers in the file.

9. A filing device according to claim 8, wherein the hook means is carried on a lateral extension

of the filing base adjacent the paper engaging members.

10. A filing device according to claim 1, wherein the loop engaging means permits of the slack in the loop being taken up to a greater or lesser extent according to the variable thickness of the papers to be accommodated while keeping the loop substantially taut.

11. A filing device according to claim 1 including a filing base on which the main paper engaging members are mounted, a horizontally contractile extension of said base on which the auxiliary members are mounted and said loop engaging means being in the form of at least one hook member also mounted on the said extension of the base.

HANS ROBERT FEDERN.
